UNITED STATES PATENT OFFICE.

WILLIAM E. STEVENS, OF NEW HAVEN, CONNECTICUT, ASSIGNOR TO
SARGENT & CO., OF SAME PLACE.

DESIGN FOR A COFFIN-SCREW.

SPECIFICATION forming part of Design No. 15,499, dated October 28, 1884.

Application filed August 18, 1884. Term of patent 14 years.

To all whom it may concern:

Be it known that I, Wm. E. STEVENS, of New Haven, in the county of New Haven and State of Connecticut, have invented a new Design for Coffin-Screws; and I do hereby declare the following, when taken in connection with accompanying drawing, and the letters of reference marked thereon, to be a full, clear, and exact description of the same, and which said drawing constitutes part of this specification, and represents a side view.

This design relates to that class of coffin-screws which are of a knob-like character, and have the appearance of a canopy hanging over the head; and the invention consists in the configuration of the canopy, as shown in the accompanying illustration, and hereinafter described.

A represents the knob or body of the screw.
On the top is a raised convex center, *a*, from

which the canopy springs, the canopy inclining downward and outward, presenting a series of facets, *b*, each facet at the lower edge rounded, so as to form a series of scallops around the lower edge, corresponding to the series of facets on the canopy, and as shown in the accompanying illustration.

I claim—

The herein - described design for coffin-screws, consisting of the knob-shaped body A, with a canopy representing a series of facets inclined downward and outward from the center, their lower edge of rounded shape, and forming a series of scallops corresponding to the series of facets, as shown in the accompanying illustration.

WILLIAM E. STEVENS.
